UNITED STATES PATENT OFFICE.

WALTER C. LINDEMANN, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

METAL DOOR FOR OVENS AND THE LIKE.

Application filed September 27, 1924. Serial No. 740,156.

To all whom it may concern:

Be it known that I, WALTER C. LINDEMANN, a citizen of the United States, and a resident of the city of Milwaukee, in the 5 county of Milwaukee, State of Wisconsin, have invented certain new and useful Improvements in Metal Doors for Ovens and the like, of which the following is a specification.

10 This invention relates generally to the mounting of hinged closure members such as oven doors and more particularly to improvements in hinge and closure structures for use with closure members of this type.

15 In the manufacture of stoves and ranges of the type in which ovens are provided considerable difficulty has been had in the effective mounting of the hinged doors used with such ovens in that the providing of 20 suitable hinges for such doors has presented a particular problem for the reason that a hinge structure adapted for this purpose has not heretofore been provided which successfully combined a satisfactory mechanical 25 effectiveness of operation together with a relatively low cost of manufacture. The provision of satisfactory journal or pintle members for the hinge structures has called for comparatively expensive cutting and 30 machining operations which is obviated by the use of the hereinafter described hinge structure.

The invention includes a hinge joint in which the bearing member is carried by the 35 door or closure device and consists merely of a rounded notch suitably disposed in a bracket member projecting from the lower extremity of the door. The complementary, that is, the journal or pintle member, 40 takes the form of a removable cylindrical section formed of sheet steel, or other suitably resistant material, the journal member being removably mounted in the lower end of a vertical slot in the wall of the oven 45 through which the bearing member on the door projects.

Another feature of the invention consists in an improved latch or locking device of the spring pressed type which automatically 50 engages with a keeper when the door is swung to closed position to hold the door closed until the latch is deliberately moved

to releasing position by the act of an operator.

Other features of the invention will be 55 hereinafter referred to.

In the drawings, in which a preferred embodiment of the invention has been selected for illustration,

Figure 1 is a view in front elevation of an 60 oven door equipped with hinge and latch devices embodying the invention.

Figure 2 is a view in side elevation and partly in section of the parts shown in Figure 1.

Figure 3 is a plan view of a hinge journal or pintle member forming part of the invention.

Figure 4 is an end view of the device shown in Figure 3.

Figure 5 is a longitudinal sectional view taken on the line 5—5 of Figure 4.

Figure 6 is a view showing a method of mounting the journal member shown in Figure 3 in position to receive the bearing 75 portion of the hinge structure.

Figure 7 is a view of the parts shown in Figure 1 taken from the inside of the door and with parts broken away to show the internal construction.

Figure 8 is a sectional view taken on the line 8—8 of Figure 7; Figure 9 is an enlarged detail of the latch and adjacent parts as shown in Figure 8.

Referring to the drawings for a more 85 detailed description of the invention, at 10 there is shown an oven door construction mounted in hinged relation to the framework 11 of the oven in connection with which the door 10 is used. The oven door 90 10 is hinged to rock about its lowermost extremity on a horizontal axis so that in order to open the door the handle member 12 is grasped and the door is swung outwardly and downwardly to provide access to the 95 oven. The opposite extremities of the lowermost portion of the door 10 are provided with laterally extending lugs 13 which serve to support hinge member 14 which enter slots 15 formed in the oven framework 100 11 outside the lateral edges of the oven door opening. The hinge members 14 have a hook-shaped conformation and extend inwardly through the frame member 11 and

are attached through suitable spring members 16 to suitable points on the frame-work in order to assist or facilitate the swinging of the oven door to its raised or closed 5 position.

The hinge members 14 form in effect bearing members in that they are provided in their rearward edges with rounded notches 17 which are adapted to turn on journal 10 members 18 which have the formation of split hollow cylindrical sections fitted into place at the lower ends of the slots 15 in the oven framework 11.

In order to fit the journal members 18 securely in immovable position in the receiving slots 15, the cylindrical sections are split throughout their lengths along one side and are provided with notches 19 in positions diametrically opposite the slotted opening 20.

With this construction the journal member 20 may be fitted into position as is shown in Figure 6 of the drawing by tilting the cylindrical section as at A and then swinging it to its horizontal position as at B so that

25 when in its final horizontal position at the bottom of the slot 15 the notches 19 receive the lateral edges of the slot 15. It will be clear that the portion 21 of the cylindrical shell 18 included between the inner ends of the notches 19 is of the same length as the width of the slot 15 so as to prevent longitudinal movement of the cylinder 18 resting in its operative position at the bottom of the slot. The passing of the slotted portion 21 of

35 the cylinder 18 downwardly below the lower edge of the slot 15 prevents rotation of the cylinder 18 on its seat so that an immovable and cylindrical journal or pintle member is formed on which the hinge member 14 of the 40 door turns in swinging the door to its open or closed position.

The provision of the detachable or removable journal members 18 obviates the necessity for providing a machined or turned cylinder member in the wall of the oven frame member and also does away with the use of cylinder members carried by brackets which would require the use of screws or bolts for holding the parts in position. I am thus 45 enabled to effect a considerable economy in the manufacture of hinge parts of this general nature and, in addition, an effective and easily operable hinge structure is provided. Because of the shell or skeleton-like nature of 55 the hollow journal member a considerable heat insulating effect is provided which insures the operation of the parts without interference by expansion effects.

The handle member 12 referred to is connected directly to the outer frame member of the oven door 10 so that a pull exerted on the handle will swing the door outwardly from its closed position. A latch member 22 is carried between the inner and outer shells 60 of the door 10 and projects upwardly into a

keeper 23 formed in the frame member 11 when the door is swung to closed position. The latch member or bolt 22 is provided with laterally extending spring extension members 24 which may be formed integrally therewith. The spring extension members 24 are so engaged by inwardly extending brackets or lugs 25 carried by the outer wall of the door casing that the latch is under constant tension to move upwardly into position to engage the keeper 23. At the same time the disposition of the spring engaging lugs 25 permits the retraction of the wedge-shaped catch 22 when a push or pull is exerted on the door through the handle member 12. 70 75 80

When the door 10 is swung outwardly and downwardly to its lowermost position, the inner extensions 26 of the hinge members 14 are so formed that they will engage the inner wall of the frame member 11 above the slots 15 and serve as stop members to prevent an excessive opening movement of the door. 85

One of the features of the latch is that it is held in position entirely by the door lining by means of the lugs 25 and the lining, proper, which prevents the spring extension members 24 from moving laterally. The said extension members may be made of sufficient width to fit loosely between the walls of the door and thus be held by said walls against such movement. 90 95

What I claim is:—

1. In a hinged-door construction, a frame member provided with apertures adjacent the opposite extremity of the lower edge of the door opening, a door, and hinge members carried by the door adjacent the lower edge thereof, said hinge members being formed and arranged to extend through said perforations, to substantially fill the same at closed position so as to prevent substantial vertical movement, and to have bearing support therein in the opening and closing movements of the door and a latch at the upper part of the door adapted to hold said hinge members in engagement with said bearings. 100 105 110

2. In a hinged-door construction, a frame member provided with apertures adjacent the opposite extremities of the lower edge of the door opening, a door, hinge members carried by the door adjacent the lower edge thereof, said hinge members being formed and arranged to extend through said perforations, to substantially fill the same at closed position so as to prevent substantial vertical movement, and to have bearing support therein in the opening and closing movements of the door and a latch at the upper part of the door adapted to hold said hinge members in engagement with said bearings, and said hinge members being provided with extensions acting to engage the inner surface 115 120 125 130

of the frame member to limit the extent of opening of the door.

3. In an oven-door construction, a frame member provided with slots adjacent the opposite extremities of the lower edge of the door opening, removable journal members mounted in the slots, and hinge bearing members carried by the door, said hinge bearing members being formed to extend through said slots and to have bearing support on said journal members and a latch at the upper part of the door adapted to hold said hinge members in engagement with said bearings.

15 4. In an oven-door construction, a frame member provided with slots adjacent the opposite extremities of the lower edge of the door opening, journal members in the form of removable cylindrical members mounted in the slots, and hinge members carried by the door, said hinge members being formed to extend through said slots and provided with rounded notches for bearing engagement with the cylindrical members.

25 5. In an oven-door construction, a frame member provided with slots adjacent the opposite extremities of the lower edge of the door opening, journal members in the form of split cylindrical shells mounted in the slots with the lower edges of the slots received in the clefts in the shells, and hinge members carried by the door, said hinge members being formed to extend through said slots and provided with rounded notches for bearing engagement with the cylindrical members.

40 6. In an oven-door construction, a frame member provided with slots adjacent the opposite extremities of the lower edge of the door opening, journal members in the form of removable cylindrical members mounted in the slots, hinge members carried by the door, said hinge members being formed to extend through said slots and provided with rounded notches for bearing engagement with the cylindrical members, and stop members carried by the hinge members for engaging the frame member to limit the extent of opening of the door.

50 7. In an oven-door construction, a frame member provided with slots adjacent the opposite extremities of the lower edge of the door opening, journal members in the form of split cylindrical shells mounted in the slots with the lower edges of the slots received in the clefts in the shells, hinge members carried by the door, said hinge members being formed to extend through said slots and provided with rounded notches for bearing engagement with the cylindrical members, and stop members carried by the hinge members for engaging the frame member to limit the extent of opening of the door.

65 8. In an oven-door construction, a frame member provided with slots adjacent the

opposite extremities of the lower edge of the door opening, journal members in the form of split cylindrical shells mounted in the slots with the lower edges of the slots received in the clefts in the shells, said shells being provided with end notches to receive the side edges of the slots, hinge members carried by the door, said hinge members being formed to extend through said slots and provided with rounded notches for bearing engagement with the cylindrical shells, stop members carried by the hinge members for engaging the frame member to limit the extent of opening of the door, and spring means engaging the hinge members to assist in swinging the door to closed position.

9. A hinged door construction for ovens comprising a frame having an opening adapted to be closed by a door, a portion of said frame extending inwardly from the outer face thereof along the upper edge of said opening, a door hinged near the opposite edge of said opening, hinges therefore within the outer portion of the door said door having a body portion adapted to fit the opening and close the same and an overlapping portion extending beyond said body portion outside the opening and overlapping the vertical edges thereof to form a seal closing and protecting the crack between said body portion and said edges of the opening, a spring extending member on one of said members and a recess in the other both within the outer face of said frame when the door is in closed position, said spring member and recess acting as a latch to hold the door in such position.

10. In a hinged-door construction, a frame member provided with apertures adjacent the opposite extremity of the lower edge of the door opening, a door, and hinge members carried by the door adjacent the lower edge thereof, said hinge members being formed and arranged to extend through said apertures and to have bearing support therein in the opening and closing movements of the door, said frame having an inturned portion at the upper edge of said door opening having a recess therein for the reception of a latch, a spring latch carried by the door and within the portion of the door which is exposed when the said door is closed, said latch being within the plane of said aperture when said hinge members bear on the edges of said apertures.

11. In a hinged-door construction, a frame member provided with apertures adjacent the opposite extremity of the lower edge of the door opening, a door, and hinge members carried by the door adjacent the lower edge thereof, said frame having an inturned portion at the upper edge of said door opening having a recess therein for the reception of a latch, a spring latch carried by the

door and within the portion of the door which is exposed when the said door is closed, said latch comprising a tapered outer portion for engagement with said recess extending beyond the said door and inwardly and laterally extending spring portions within in the said door and enclosed therein.

12. A structure as specified in claim 1 in combination with a spring latch member 10 projecting beyond the upper edge of the door, so formed and arranged as to be depressed by the adjacent edge of the frame member on the closing of the door, said frame having a recess within its outer face to receive the spring latch and the said hinge members having recesses to receive the edges of the perforations approximately in vertical plane with the said latch receiving recess and distant therefrom the width of the door.

13. An oven door construction comprising a frame having a door opening, a door for said opening, a latch at one edge of said door and a hinge construction at the opposite edge comprising a vertical slot in the frame and a hinge member secured to the door and extending through said slot con-

sisting of a substantially flat angular member having a notch or recess adjacent the door and being of a width to substantially fill the slot adjacent the door and prevent 30 substantial vertical movement of the same in the slot and a portion of reduced width extending away from the door to permit vertical movement of the said member in the slot. 35

14. In the construction specified in claim 13 the said hinge member having its edge opposite the recess eccentric thereto.

15. In the construction specified in claim 9, the hinges comprising lateral extensions 40 near one edge of the door and inwardly extending portions projecting from within the outer edges of said extension through the frame, said lateral extensions covering the portion of the frame through which said inwardly extending portions extend. 45

Witness my hand this 13th day of September, 1924, at the city of Milwaukee, in the county of Milwaukee, State of Wisconsin.

WALTER C. LINDEMANN.
